Application May 10, 1946, Serial No. 668,802

15 Claims. (Cl. 219—46)

1

This invention relates to electric heating pads of the type having a plurality of different selectable heats. The present application is a continuation in part of my copending application Serial Number 642,938, filed January 23, 1946, and entitled "Electric heating pad."

In a prior type of heating pad having three fixed heats, low, medium and high, an organization was employed which included a control thermostat located in the jacket of the pad close to the heating element, and included a three-point selector switch in the supply cord of the pad, the said switch having two resistor elements connected in series, the outer or remote ends of the elements being joined respectively to the outer contacts of the switch, and the common connection of the elements joining with the middle switch contact. This prior pad was found to be generally satisfactory in operation, but according to the circuit and organization employed, in order to obtain a very low pad heat and a considerable spread or range between the low and the medium and high heats of the pad which was found to be desirable, the resistor elements in the switch, which were wire wound, had to be of relatively high ohmage. Because of the small space available in the switch for the resistor elements, this presented a problem since room was not available to take resistors of very high ohmage, and as a result a compromise was effected between the ohmage of the elements and the spread or range between the heat settings of the pad. Also, in this prior pad, one or both of the resistor elements produced heat in the switch during the low and medium settings of the latter, which settings are normally in frequent use. While this heat was not sufficient to cause a dangerous condition, it resulted in the switch becoming warm to the touch, giving rise to doubt in the mind of a user as to the operativeness of the pad, and this warmth was evident unless the pad was used solely for high heat, wherein the resistor elements were not energized.

The present invention overcomes the difficulties enumerated above in connection with the prior type of heating pad. In accomplishing this, a simple and novel organization is provided wherein, for the low heat setting of the selector switch of the pad, the resistor element or elements in the switch are not in use, being disconnected and unenergized. According to the circuit employed, for the low heat switch setting, the entire current which is consumed passes serially through the heater for the thermostat and through the pad coils, producing a high heat in

the thermostat and resulting in the pad being maintained at a low temperature, herein termed "low-low," which is considerably below the low setting of the prior type pad, and provides a distinct advantage in situations where low temperatures are desired. As a consequence, also, the spread or range between the low, and the medium and high settings of the pad of the present invention is considerably greater than the spread or range between the corresponding settings of the prior pad, and these results are all achieved without resorting to resistors of high ohmage in the selector switch of the pad.

In addition to the above advantages, the operation of the pad is such that the heating of the switch casing is generally reduced and is less noticeable. This is because current is made to pass through the resistor element or elements of the switch only for the medium or intermediate settings of the latter. For both the high and low settings of the switch, which are frequently used, the resistor means is not energized. Thus, the switch casing is on the average cooler and less likely to be noticeably warm to the touch.

25 In one specific embodiment of the invention illustrated herein a three-point fan-blade selector switch is employed, and but a single resistor element of relative low ohmage is provided, connected between one of the outer contacts of the switch and the middle switch contact. The selector switch has a two-arm fan blade which when set in one position spans one pair of adjacent contacts of the switch, and when set in another position spans the other pair of adjacent contacts. The switch blade may be also so positioned as to engage solely the first outer contact of the switch.

According to the circuit provided, the energizing current may be made to pass serially through 40 the thermostat heater, thermostats and heating coils of the pad without being diverted either in whole or in part through the resistor in the selector switch. This condition is effected by the lowest setting, marked "low-low" of the selector switch, and results in a relatively low pad heat substantially lower than that in the prior pads of this type, and considerably removed from the range of the medium and high pad heats, without resorting to high ohmage resistors in the selector switch. When the switch is set on medium, the resistor element of the switch is shunted across the thermostat heater, and a part of the current is thus diverted from the heater by the resistor element, causing the heater to operate at a lower temperature, thereby increasing the pad temper-

ature. For the high setting of the selector switch, the energizing current does not pass through the resistor element of the switch at all, nor through the thermostat heater of the pad, but instead is conducted solely through the pad thermostats and the heating coils of the pad.

In another embodiment of the invention, comprising a four-heat pad, the selector switch has an additional contact, which is interposed between the first or "low-low" and the second or "medium" contacts, and has an additional resistor element connected between the additional contact and the immediately following or succeeding contact. By this organization an additional setting or heat of the pad is obtained, located between the low and medium pad heats. Due to the fact that a substantial spread or range exists between the "low-low" and medium pad heats, the inclusion of this fourth heat, which is termed herein a "low" heat, is of advantage since it provides for finer adjustment of the pad temperature.

In still another embodiment of the invention the heat control switch does not have individual contacts but instead a continuously variable resistor element, preferably of an ohmage equivalent to the combined ohmage of the two resistor elements of the four-heat switch of the second embodiment, above. The organization of the switch with the continuously variable resistor element is such that current may be passed through the switch either directly to the thermostat heater, or to the heating coils of the pad without being diverted either in whole or in part through the resistor element of the switch. Thus, a wide spread is obtained between the "low-low," and the high heats of the pad without the use of extremely high ohmage in the switch resistor, and also a large number of graduated heats may be obtained in the pad, located between the range of the low heat of the four-heat pad and the high heat of the latter, providing for extremely fine adjustment of the pad temperature.

Other features and advantages will hereinafter appear.

In the accompanying drawings:

Figure 1 is a diagrammatic representation of a heating pad made in accordance with one embodiment of the invention.

Fig. 2 is a diagrammatic representation of a switching control for use with the pad proper of Fig. 1, illustrating another embodiment of the invention, and

Fig. 3 is a diagrammatic representation of another switching control for use with the pad of Fig. 1, and illustrating a third embodiment of the invention.

The heating pad shown in Fig. 1 comprises a jacket 10 indicated in dotted outline, enclosing and carrying a usual type of heating element or coil 11, and having embedded therein at two different locations respectively a safety thermostat switch 12 and a control thermostatic switch 13. The thermostatic switch 13 has a heater 14 associated with it, one end 15 of the heater being connected with one terminal of the switch 13 and also connected with a wire 16 passing through a supply cord 17 leading from the jacket 10. The other end 18 of the heater 14 is connected to a wire 19, also extending through the supply cord 17.

The other terminal 20 of the control thermostat 13 is connected by a wire 21 with one terminal 22 of the safety thermostat 12, and the remaining terminal 23 of the safety thermostat

is connected by a wire 24 with one end 25 of the heating element 11. The opposite end 26 of the heating element is in turn connected with a line wire 27 passing through the supply cord 17.

According to the present invention a novel resistor-type control, mounted in a single casing, is provided in the supply cord 17, the said control enabling the heating coils 11 of the pad to be operated at a low temperature which is substantially less than the low temperatures of previous resistor-controlled pads. Also, the control is so arranged that the casing thereof is on the average cooler than in prior pads having resistor-type controls, and is therefore less likely to be noticeably warm to the touch.

The control comprises, in the embodiment of Fig. 1, a continuously variable resistor 28 which is mounted in a switch casing diagrammatically indicated at 29 in broken outline. The resistor 28 comprises a resistance element 30 having one end secured to a contact and terminal 31, the other end 32 of the element being free or unconnected. A movable contactor 33 is provided for engagement with the element 30, the said contactor being slidable on the element so that the resistance between the terminal 31 and the contact 33 is substantially continuously variable from zero to a value determined by the total ohmage of the resistance element.

For engagement with the movable contactor 33 the resistor 28 has a contact bar 34, the said bar making electrical connection with the contactor throughout the engagement of the latter with the resistor element 30, and also connecting with the contactor when the latter is in the position indicated at 36, located beyond the free end 32 of the element and out of engagement therewith. A dead stationary contact 37 is shown at this position.

Also, the resistor 28 is so constructed that the contactor 33 may be moved out of engagement with the bar 34, as shown by the position the contactor occupies in Fig. 1, (represented by full lines).

Connections of the control are as follows: The wire 19 in the cord 17 is connected with the contact bar 34 of the resistor 28, and the wire 16 of the cord is connected with the terminal 31 of the resistor. The wire 27 of the cord 17 passes through the casing 29 and constitutes a supply line for the heating pad, and a second supply line 38 is connected with the movable contactor 33.

For purposes of illuminating the switch or control unit, a gaseous glow lamp 39 is mounted in the casing 29 and connected through a series current-limiting resistor 40 to the contact bar 34, and through a wire 41 to the line wire 27.

According to the above organization provided by the invention, a very low pad heat is obtainable when the contactor 33 is in the position 36 indicated in Fig. 1, the said heat being termed herein a "low-low" heat, since it is substantially less than the "low" heat of prior pads having resistor-type controls. For this position of the contactor 33 the energizing current passes serially through the thermostat heater 14, through the thermostats 13 and 12, and through the heating coils 11 of the pad, without being diverted in part from the thermostat heater, and the latter is thus energized to produce a high heat which actuates the control thermostat 13 so as to produce a very low heat in the coils 11 of the pad.

When the contactor 33 is moved to the position 36a shown in Fig. 1, wherein it engages the free or unconnected end 32 of the resistance ele-

ment 30, the said element is shunted across the thermostat heater 14 and diverts a part of the current from the latter. As a result, the heater 14 operates at a somewhat lower temperature causing the control thermostat 13 to respond so as to produce a heat in the coils 11 which is higher than the "low-low" heat. This higher heat is termed herein a "low" heat, since it is the same as the corresponding "low" heat of prior pads having resistor-type control switches.

As the contactor 33 is moved along the resistance element 30 toward the "high" position wherein it engages the contact 31, more and more of the current will be diverted from the heater 14 of the control thermostat 13, causing a lesser heating of the heater and a consequent higher temperature in the pad coils 11. When the contactor 33 engages the contact 31 at the "high" position, the thermostat heater 14 will be short circuited and substantially no current will pass through it. For this condition, the thermostatic switch 13 responds solely to heat from the coils 11 of the heating pad and the latter are therefore maintained at their highest operating temperatures.

When the contactor 33 is in the "off" position, it does not engage the contact bar 34, and the pad is thus deenergized, since no current flows through any of the circuits.

It will be obvious that the lamp 39 is also deenergized for the "off" position of the contactor 33, and is fully energized for the remaining, energizing positions of the contactor, thereby providing a visual indication at the control when the pad circuits are energized.

It will be seen that, by the above organization, the heating coils 11 of the pad 10 may be controlled to produce a very low heat in the pad without resorting to the use of extremely high resistance in the element 30, since the said element is not energized for the "low-low" setting of the control. Thus, there is not present the problem of providing a resistance element of extremely high ohmage for use in the constricted space within the switch casing 29, which problem has heretofore defeated attempts to produce a very low heat in pads of this type, and to produce a wide spread between the lowest and highest heats of the pad.

Moreover, due to the fact that for the "low-low" and "high" settings of the control, the resistance element 30 thereof is not energized, no heat is produced within the switch casing 29 for these settings. It is only for the settings of the control located between the "low-low" and the "high" position that the element 30 is energized, in contradistinction to the prior heating pads wherein the element is energized for all except high settings. As a consequence, on the average, the heat produced in the switch casing 29 is less, and the casing is therefore generally cooler to the touch than was heretofore possible to achieve.

Another embodiment of the invention is illustrated in Fig. 2, wherein a resistor-type control is provided in the form of a selector switch which has predetermined settings representing substantially different degrees of heats in the pad, the said settings being chosen to provide fairly substantial steps in contradistinction to the continuously variable control of Fig. 1.

The selector switch 42 shown is of the three-point fan blade type, and the control incorporating the switch has but a single resistor element 43, the said element bridging adjacent contacts 44, 45 of the switch. The two outer contacts 44

and 46 of the switch are connected respectively to the wires 16 and 19 of the supply cord 17 so as to be bridged by the thermostat heater 14.

The selector switch 42 includes a fan blade 47 having contact-engaging portions 48 and 49 shaped so that they can bridge either pair of adjacent contacts, 46, 45 or 45, 44. Also, the blade 47 may be positioned so that solely the portion 49 thereof engages the contact 46, or so that none of the switch contacts are engaged, the latter position being shown in the figure.

The supply wire 38 for the pad is connected with the switch blade 47, and the supply wire 27 passes through the switch casing 50 and into the body 10 of the pad.

When the blade 47 is in the "off" position wherein the portions 48 and 49 do not engage any of the contacts 46, 45 or 44, the heating element 11 is not energized, and the pad is in the cold condition. When the blade 47 is moved counterclockwise to "low" position, the portion 49 thereof engages solely the switch contact 46 and current flows from the line wire 38 through the wire 19, thermostat heater 14, thermostat 13, wire 21, safety thermostat 12, wire 24, and through the heating element 11 to the return supply wire 27.

This energizes the heating coils 11 of the pad so that the heating thereof is in the "low-low" range, similar to that described in connection with Fig. 1.

When the switch blade 47 is shifted to the "medium" setting, the portions 48 and 49 of the blade 47 engage the switch contacts 45 and 46. Current thus flows through both the resistor 43 and the thermostat heater 14, which are now in parallel, and thence through the thermostats 13 and 12, and the heating element 11 to the line wire 27. By this connection less current flows through the thermostat heater 14 than for the "low-low" setting of the switch, and consequently the thermostat 13 is operated so as to maintain the heating element and pad at a higher temperature, which is termed the "medium" heat of the pad.

When the switch blade 47 is rotated still further counterclockwise so that the portions 48, 49 thereof engage the switch contacts 45, 46, respectively, the thermostat heater 14 is cut out of the circuit, and the resistor 43 is shunted out, and current flows through the wire 16 directly through the thermostat 13, and thence through the thermostat 12 and heating element 11 to the return supply wire 27. For this setting of the switch, the control thermostat 13 is operated solely in response to the heat from the heating element 11, and consequently the thermostat operates to maintain the pad at a still higher temperature than that provided by the previous switch setting. This higher temperature is termed the "high" heat of the pad.

Another embodiment of the invention is illustrated in Fig. 3. The control 51 shown herein is similar in a number of respects to the control 42 shown in Fig. 2, and therefore like parts have been given like characters. However, in the control 51 the fan blade 51a has three arms 51b, 51c and 51d, and a fourth stationary contact 52 is provided, located between the stationary contacts 45 and 46. Also, a second resistor element 53 is connected between the contact 52 and the contact 45. A fourth position is thus added to the control, this position being termed "low" since it corresponds with the low heat of prior pads

of this type, and this position is indicated at 54 in the figure.

The provision of the fourth setting, as incorporated in the control 51, is of distinct advantage in providing for a finer adjustment of the pad heat, in view of the fact that a substantial spread may exist between the "low-low" heat of the pad and the "medium" heat of the pad, as determined by the value of the resistor element 43.

It will be understood that when the blade 51a is in the "off" position shown in the figure, no current will flow through the pad circuits and the pad will thus be cold. When the blade is shifted so that the arm 51d thereof engages the stationary contact 46, current will flow through the thermostat heater 14 without being diverted, and this will cause the pad to operate at the "low-low" heat. When the blade 51a is shifted to the "low" setting, the arms 51c and 51d will respectively engage the contacts 46 and 52, and current will divide between the thermostat heater 14 and the series-connected resistors 53 and 43. This reduces the current of the heater 14 and causes the thermostat 13 to operate the pad at the standard "low" temperature.

As the switch blade 51a is shifted to the "medium" setting, the arms 51b, 51c and 51d of the blade will respectively engage the contacts 46, 52 and 45. This short circuits the resistance element 53, and causes the energizing current to be divided between the element 43 and the heater 14, resulting in a still lesser heat of the latter, and a still higher pad temperature. In the "high" setting of the fan blade 51a, the resistance elements 43 and 53 will be shunted out, and the heater 14 will also be cut out of the circuit. Current will thus flow serially through the thermostats 13 and 12 of the pad, and through the pad coils 11, and the heat from the latter will be the sole means for actuating the thermostat 13. As a consequence the pad coils will be maintained at their hottest operating temperatures.

By the organization provided in Fig. 3 a considerable spread or range is possible between the "low-low" and the "high" heats of the pad, and the said range is so divided that two intermediate heats are obtainable. This not only provides a desirable overall choice of heats, but also so enables the pad to be operated at a very low temperature, such as may be indicated in certain forms of treatments.

Variations and modifications may be made within the scope of this invention and portions of the improvements may be used without others.

I claim:

1. In a heating device, a thermostatic switch; a heater for the thermostatic switch; a resistor, said heater and resistor at one point each having a common connection; a pair of current supply wires; means for selectively connecting one of the current supply wires either solely to another point on the heater, or to the said other point on the heater and simultaneously to another point on the resistor, or to the said common connection of the resistor and heater; and electric heating means connected with the said common connection of the resistor and heater and with the other current supply wire, the said thermostatic switch controlling the circuit of the said heating means.

2. In a heating device, a thermostatic switch; a heater for the thermostatic switch; a resistor, said heater and resistor at one point each having a common connection; a pair of current supply wires; means for selectively connecting one of the current supply wires either solely to an-

other point on the heater, or to the said other point on the heater and simultaneously to another point on the resistor, or to the said other point on the heater and simultaneously to still another point on the resistor, or to the said common connection of the resistor and heater; and electric heating means connected with the said common connection of the resistor and heater, and with the other current supply wire, the said 10 thermostatic switch controlling the circuit of the said heating means.

3. In a heating device, a heating element; a thermostatic switch controlling the circuit of the heating element; a heater for the thermostatic switch; a resistor, said heating element, heater and resistor having ends connected with each other, constituting a common connection; means for connecting one leg of a current supply with the other end of the heating element; and means for selectively connecting the other leg of the current supply either solely to the other end of the heater for the switch, or simultaneously to the other ends of both the resistor and the heater for the switch, or to the other end of the heater and simultaneously to an intermediate point on the resistor, or to the said common connection of the heating element, resistor, and heater for the switch.

4. In a heating device, a heating element; a 30 thermostatic switch controlling the circuit of the heating element; a heater for the thermostatic switch; a resistor, said heating element, heater and resistor having ends connected with each other, constituting a common connection; means for connecting one leg of a current supply with the other end of the heating element; and means for selectively connecting the other leg of the current supply either solely to the other end of the heater for the switch, or to the other ends of both the resistor and the heater for the switch, or to the other end of the heater and simultaneously to any of a plurality of intermediate points on the resistor, or to the said common connection of the heating element, resistor, and heater for the switch.

5. In a heating device, a heating element; a 50 thermostatic switch controlling the circuit of the heating element; a heater for the thermostatic switch; a resistor, said heating element, heater and resistor having ends connected with each other, constituting a common connection; means for connecting one leg of a current supply with the other end of the heating element; and means for selectively connecting the other leg of the current supply either solely to the other end of the heater for the switch, or to the other ends of both the resistor and the heater for the switch, or to the other end of the heater and simultaneously to any of a plurality of closely spaced intermediate points on the resistor, or to the said common connection of the heating element, resistor, and heater for the switch, thereby to obtain fine adjustment of the heat of the heating element.

6. In a heating device, a heating element; a 65 thermostatic switch controlling the circuit for the heating element; a selector switch having four stationary, consecutively arranged contacts and a triple arm fan blade, said blade being shaped to span any three consecutive stationary contacts, and the blade being mounted to engage either solely the first contact of the switch, or the first two switch contacts, or three consecutive contacts; a resistor element connected between the fourth and third stationary contacts

of the selector switch; a second resistor element connected between the third and second stationary contacts of the selector switch; a heater for the thermostatic switch, connected between the first and fourth contacts of the selector switch; and current supply means connected with the fan blade and with one end of the heating element, the other end of the element being connected with the said first contact of the selector switch.

7. In a heating device, a heating element; a thermostatic switch controlling the circuit of the heating element; a heater for the thermostatic switch; a continuously variable resistor having two terminals, and having an open-circuit position, said heating element and heater having ends connected to one terminal of the resistor, and the other end of the heater being connected to the other terminal of the resistor; and means including a switching mechanism for connecting one leg of a current supply with the said other terminal of the variable resistor, the other leg of the current supply being connected to the other end of the said heating element.

8. In a heating device, a heating element; a thermostatic switch controlling the circuit of the heating element; a heater for the thermostatic switch; a continuously variable resistor having a resistance element, a contact movable between limits and in opposite directions over the said element, said contact adjacent one limit of its movement being separable from the element, and the said resistor having a current-conducting bar engaged by the contact during its movement, the said contact, when moved to the said one limit and subsequent to its separation from the resistance element, separating from the bar; means connecting the current-conducting bar with one end of the heater for the thermostat, the other end of the heater and one end of the heating element being connected to one end of the resistance element of the resistor; and a pair of current supply wires, connected respectively to the other end of the heating element and to the contact of the said variable resistor.

9. In a heating device, a heating element; a thermostatic switch controlling the circuit for the heating element; a selector switch having three stationary contacts and a fan blade, said blade selectively spanning either pair of adjacent contacts or connecting to one of the outside contacts of the switch; a heater for the thermostatic switch, connected across the outside contacts of the selector switch; a resistor connected between the center contact and the other of the outside contacts of the selector switch; and current supply means connected with the fan blade and with one end of the heating element, the other end of the element being electrically connected with the said one outside contact of the selector switch.

10. In a heating device, a heating element; a thermostatic switch controlling the circuit of the heating element; a heater for the thermostatic switch; a resistor, said heating element, heater and resistor having ends electrically connected with each other, constituting a common connection, and said thermostatic switch being connected between the heating element and the said common connection; means for connecting one leg of a current supply with the other end of the heating element; and means for selectively connecting the other leg of the current supply either solely to the other end of the heater for the switch, or to the other ends of both the resistor

and the heater for the switch, or to the said common connection of the heating element, resistor, and heater for the switch.

11. In a heating device, a heating element; a thermostatic switch controlling the circuit for the heating element; a selector switch having three stationary contacts and a fan blade, said blade selectively spanning either pair of adjacent contacts or connecting to one of the outside contacts of the switch; a heater for the thermostatic switch, connected across the outside contacts of the selector switch; a resistor connected between the center contact and the other of the outside contacts of the selector switch; and current supply means connected with the fan blade and with one end of the heating element, the other end of the element being connected through the said thermostatic switch to the said one outside contact of the selector switch.
12. A heating pad comprising a heating element; a jacket enclosing and supporting the element; a thermostatic switch located in the said jacket, controlling the circuit for the heating element; an electric supply cord leading from the jacket; a selector switch connected in the supply cord at a point removed from the jacket, said switch having three stationary contacts and a fan blade which latter selectively spans either pair of adjacent contacts or connects to a predetermined one of the outside contacts of the switch; a heater for the thermostatic switch, located adjacent the latter and connected through the said supply cord across the outside contacts of the selector switch; a resistor located within the selector switch and connected between the center contact and the other of the outside contacts thereof; and current supply wires in the supply cord, connected respectively with the fan blade and with one end of the heating element, the other end of the element being electrically connected with the said one outside contact of the selector switch.

13. A heating pad comprising a heating element; a jacket enclosing and supporting the element; a thermostatic switch located in the said jacket, controlling the circuit for the heating element; an electric supply cord leading from the jacket; a selector switch connected in the supply cord at a point removed from the jacket, said switch having three stationary contacts and a fan blade which latter selectively spans either pair of adjacent contacts or connects to a predetermined one of the outside contacts of the switch; a heater for the thermostatic switch, located adjacent the latter and connected through the said supply cord across the outside contacts of the selector switch; a resistor located within the selector switch and connected between the center contact and the other of the outside contacts thereof; and current supply wires in the supply cord, connected respectively with the fan blade and with one end of the heating element, the other end of the element being connected through the said thermostatic switch to the said one outside contact of the selector switch.

14. A heating pad comprising electric heating means; a jacket enclosing and supporting the heating means; a thermostatic switch located in said jacket, controlling the circuit of the heating means; a heater for the thermostatic switch located adjacent the latter; an electric supply cord leading from the jacket; a resistor located exteriorly of the jacket, said resistor at one point having a common electrical connection with one point of the heater through the said supply cord, said

heating means being electrically connected at one point to the said common electrical connection; a current supply wire in the supply cord, connected with another point of the electric heating means; a second current supply wire in the supply cord; and manually operable switch means located in the supply cord at a point removed from the jacket, and bridging a gap in the cord, for selectively connecting the second current supply wire either solely to another point of the said heater, or to both the said other point on the heater and another point on the resistor, or solely to the said common electrical connection of the resistor, heater and heating means, the said resistor being mounted within the said manually operable switch means.

15. A heating pad comprising: a heating element; a jacket enclosing and supporting the element; a thermostatic switch located in the said jacket, controlling the circuit of the heating element; a heater for the thermostatic switch, located adjacent the latter; an electric supply cord leading from the jacket; a resistor located exteriorly of the jacket, one end each of said heating element and heater being electrically connected with each other, and being electrically connected through the supply cord to one end of the resistor to constitute a common electrical connection; a

current supply wire in the supply cord, connected with the other end of the heating element; a second current supply wire in the supply cord; and manually operable switch means located in the supply cord at a point removed from the jacket, said switch means including a bridging contact for selectively connecting the second current supply wire either solely to the other end of the heater for the thermostatic switch, or to the other ends of both the resistor and the heater for the switch, or to the said common electrical connection of the heating element, resistor, and heater for the switch, the said resistor being mounted within the said manually operable switch means.
